(57) **CLAIM**

The ornamental design for a vibrating pager for mobile phones, as shown and described.

DESCRIPTION

FIG. 1 is a perspective view of a vibrating pager for mobile phones showing my new design being worn by a person; FIG. 2 is a perspective view of a vibrating pager for mobile phones showing my new design;

FIG. 3 is a front elevational view thereof, taken in the direction of arrow 3 in FIG. 9;

FIG. 4 is a rear elevational view thereof, taken in the direction of arrow 4 in FIG. 9;

FIG. 5 is a right side elevational view thereof, taken in the direction of arrow 5 in FIG. 9;

FIG. 6 is a left side elevational view thereof, taken in the direction of arrow 6 in FIG. 9;

FIG. 7 is a bottom plan view thereof, taken in the direction of arrow 7 in FIG. 9;

FIG. 8 is a top plan view thereof, taken in the direction of arrow 5 in FIG. 9; and,

FIG. 9 is a view identical to FIG. 2 with descriptive legend directional arrows included which are necessary for better understanding of the drawing in accordance with 37 CFR 1084(o) and appropriate with good engineering practices, so as to best indicate in what directions previous views are taken so that nothing regarding the design sought to be patented is ambiguous or left to conjecture.

The broken lines shown are included for the purpose of illustrating portions of the vibrating pager for mobile phones that form no part of the claim.
